Inventor
Charles Spurges,

By Clarence O'Brien
Attorney

UNITED STATES PATENT OFFICE.

CHARLES SPURGES, OF DE KALB, ILLINOIS.

SWIMMING DEVICE.

Application filed September 12, 1927. Serial No. 219,035.

This invention relates to devices adapted for use by swimmers for the purpose of enabling the swimmer to assist himself in moving through the water, and consists essentially, of a handle member having a pair of hingedly mounted wings secured thereto and arranged to be open when moved in one direction and closed when moved in an opposite direction so that upon the proper manipulation of the device the same may be used by a person for pulling himself through the water in a forward direction, or if desired, may be used for movement in a vertical direction in the water whereby the action of the wings will operate to maintain the swimmer at the surface of the water.

An object of the invention is to provide an article of this character of simple and practical construction, efficient and reliable in performance, of light weight, yet at the same time strong and durable, inexpensive to manufacture, and otherwise well adapted for the purposes for which the same is intended.

Other objects and advantages reside in the special construction and combination of the various elements of the invention, reference being had to the accompanying drawings forming a part of this invention, wherein:

Figure 1 is a top plan view.

Figure 2 is an end elevational view, and, Figure 3 is a side elevational view thereof.

Referring now to the drawing in detail, the invention comprises a handle member indicated at 5 having its lower ends of reduced area whereby enabling the same to be conveniently gripped by a person, and with its upper end flared as indicated at 6 whereby to provide means for attaching a pair of hinges 7 in spaced relation at each side of the flared portion of the handle by means of which wings 8 are secured at each side thereof, with one edge of the wings extending longitudinally with respect to the upper edge of the handle.

The surface of the wings when in a spread position are disposed at right angles with respect to the handle and when arranged in folded position are adapted to rest against the opposite sides thereof. Flexible straps 9 connect the undersides of each wing with the handle whereby to prevent the wings from moving beyond a position at right

angles with respect to the handles. As shown in Figure 2 of the drawings each wing tapers toward its outer edge whereby to materially reduce the weight thereof.

The outer edge of one of the wings is provided with a section of canvas 10 or other soft material so that upon the folding of such wings in a direction toward the handle, the hand of the user will not be injured because of the contact therewith.

As shown in Figure 1 of the drawing the adjacent edges of the wings 11 are arranged in substantially close relation with each other so that the pair of wings may combine to form a relatively broad area whereby to offer a greater resistance when being drawn through the water, the edges of each wing adjacent the handle being cut-away as shown at 12 in order to accommodate the same.

One end of the handle is provided with a rivet 13 having its head extending at opposite sides of the handle above the plane of the wings and the upper surface of each wing adjacent the heads of the rivet are provided with a metallic rib 14 adapted to engage the underside of the heads of said rivet to prevent the separation of the wings from the handle should one of the hinges accidentally become broken.

It will be apparent that the device is susceptible to a number of uses, for instance, by a person learning to swim, for use by a swimmer for increasing his speed, and for assisting a person to keep at the surface of the water should he become exhausted while undertaking a long swim.

It is obvious that the device is susceptible to various changes and modifications without departing from the spirit or scope of the appended claims or sacrificing any of its advantages, and I accordingly claim all such forms of the device to which I am entitled.

I claim:

1. A device of the class described, a handle member, a pair of wings hingedly attached thereto, straps connecting the underside of the wings to the handle limiting the outward movement of the wings and a section of relatively soft material provided in one of said wings adapted to prevent injury to the hand of the user upon contact with the wings.

2. A swimming device comprising a handle member, a pair of rigid wings hingedly attached at opposite sides thereof with their adjacent edges in closely spaced parallel relation, straps connecting the under side of the wings to the handle limiting the outward movement of the wing, and a section

of resilient material provided in one of said wings and disposed in position for contact with the hand of the user, upon the inward movement of the wings. 10

In testimony whereof I affix my signature.

CHARLES SPURGES.
